Fig. 3

Fig. 4

Fig. 5

FIG. 1 is a perspective view of a thermometer or similar article showing my new design;

FIG. 2 is a front elevational view thereof;

FIG. 3 is another perspective view thereof;

FIG. 4 is a bottom plan view thereof; and

FIG. 5 is a top plan view thereof.

The dominant features of my design reside in the portions shown in full lines.

I claim:

The ornamental design for a thermometer or similar article, substantially as shown and described.
